ATTORNEY

UNITED STATES PATENT OFFICE.

MILTON L. RADTKE, OF DETROIT, MICHIGAN.

ADJUSTABLE CLAMP.

1,351,966.

Specification of Letters Patent.

Patented Sept. 7, 1920.

Application filed June 16, 1919. Serial No. 304,696.

To all whom it may concern:

Be it known that I, MILTON L. RADTKE, a citizen of the United States, residing at Detroit, in the county of Wayne and State of Michigan, have invented a new and useful Adjustable Clamp, of which the following is a specification.

This invention relates to adjustable clamps and is particularly applicable for use in assembling the brake bands which are employed in certain types of planetary transmission gearings.

The object of the invention is to provide a means for temporarily clamping the several brake bands in proper registering relation so as to facilitate assembly of the transmission, and it is a further object to yieldably space the opposed members of the clamp so that the device may be readily engaged with all of the clamping bands despite possible variations in the alinement of the lugs upon the bands, which lugs the novel clamp is adapted to embrace.

In attaining these objects the invention contemplates a clamp comprising a pair of bars adjustably spaced by springs mounted upon a pair of bolts connecting corresponding ends of said bars, the spacing of the bars being such as to permit them to snugly embrace the pairs of lugs carried by the free ends of the brake bands.

A preferred embodiment of the invention is disclosed in the accompanying drawing, wherein,

Figure 1 is a top view of the clamp engaged with the brake bands of a transmission.

Fig. 2 is a similar view of the invention *per se*, showing in section the ends of the clamp bars engaged by the bolts.

In these views, the reference character 1 designates the brake bands of a planetary transmission (not shown) and 2 the draw-rods controlling said bands. This control is effected through engagement of each rod with a pair of lugs 3, mounted in opposed relation upon the extremities of the controlled band. Between each pair of lugs a spring 4 is coiled upon the corresponding rod 2, urging the lugs and consequently the ends of the band apart.

The parts above described are old and are disclosed merely to show the application of the present invention thereto. Said invention comprises a pair of substantially

parallel offset clamping bars 5 spaced a proper distance to snugly embrace at their free ends the pairs of lugs 3, between the bands 1 and rods 2. At one end of the clamp the bars 5 are connected by a pair of 60 bolts 6 threaded into one of the bars and passing loosely through oversize apertures 7 in the other. Adjacent their ends thus connected the bars are offset outwardly as indicated at 8, so that the main portions of the 65 bars are spaced to a somewhat greater extent than their connected ends. At their free ends the opposing faces of the bars are inwardly beveled slightly, as indicated at 9, to facilitate engagement of the bars with the lugs 3. 70

When the lugs 3 have been embraced between the bars 5, as described and shown, said lugs are positively maintained in the registering relation which it is desirable to maintain in order to properly assemble the 75 transmission of which the bands 1 form a part. The bolts 6 may be adjusted to establish such a spaced relation between the bars as most suitable for the particular transmission which is to be assembled. The 80 loose engagement of the bolts within the apertures 7 allows a limited angular play between the bars under the influence of the springs and provides for yieldable movement to accommodate variations in the spacing of the several pairs of lugs. The 85 shoulders formed by the offsets 8 limit the advance of the bars 5 into engagement with lugs 3, or in case the several pair of lugs are successively inserted between the bars 5, 90 said shoulders determine the proper position for the first pair of lugs so inserted. When the brake bands have been properly positioned in the transmission, the clamp 95 may be removed.

A considerable saving of time may be effected by employing the above described clamp and properly positioning all three bands simultaneously, instead of separately manipulating each band as in the practice 100 heretofore followed.

What I claim is:

1. An adjustable clamp comprising a pair of clamping bars, and a plurality of bolts connecting corresponding end portions of 105 said bars, said bolts being threaded into one of the bars and passing through oversize apertures in the other.

2. An adjustable clamp comprising a pair of clamping bars, a plurality of bolts con- 110

necting corresponding end portions of said bars, said bolts being threaded into one of the bars and passing through oversize apertures in the other, and a spring coiled upon one of said bolts and urging said bars apart.

3. An adjustable clamp comprising a pair of clamping bars, and a plurality of bolts connecting corresponding end portions of 10 said bars, said bolts being threaded into one of the bars and passing through oversize apertures in the other, said bars being offset adjacent their connected ends to form

shoulders for positioning parts engaged between said bars.

4. An adjustable clamp comprising a pair of spaced clamping bars, members connecting corresponding end portions of the bars rigidly engaging one of the same and passing loosely through the other, and means 20 yieldably urging the connected ends of the bars apart.

In testimony whereof I sign this specification.

MILTON L. RADTKE.
